PROFILE DRESSER FOR ABRASIVE WHEELS

Edward A. Johnson and Alexander A. Emelianoff, New York, N. Y.

Application June 30, 1938, Serial No. 216,736

10 Claims. (Cl. 125—11)

The present invention relates to the art of abrading, and more particularly to novel apparatus for dressing abrasive wheels, being particularly applicable as an attachment for surface grinding machines to generate any desired profile upon the working surface of the abrasive wheel thereof to the end that such profile may be imparted to the work. The invention is particularly, but not exclusively, adapted for use 5 with surface grinders of the type commonly used in the precision mechanical trades for forming very precise plane surfaces upon hardened steel pieces, such as tool and die parts. Such surface grinders ordinarily comprise a rotatable spindle 10 upon which is mounted an abrasive wheel adapted to be rotated at high velocity in contact with the work which is secured to a reciprocable platen by means of a magnetic chuck.

Abrading machines or surface grinders are 20 commonly utilized to impart very smooth plane surfaces to the work; but it is desirable to extend the range of utility of such machines to include the production of other than plane surfaces; that is, profiles, consisting of various combinations 25 of radial and tangent lines, the inter-dimensional relationship of which are very precise.

Abrasive wheels are ordinarily dressed or trued up by applying a diamond point to their working surfaces while rotating the same at high speed. 30 Accordingly, it is desirable, in carrying out the production of complex profiles in a surface grinder to first prepare the working surface of the abrasive wheel by dressing or shaping the same with a diamond point to correspond to the desired 35 profile, and then impart this profile to the work by reciprocating the same while in contact with the prepared working surface of the abrasive wheel.

The apparatus according to the invention includes 40 instrumentalities applicable to hold a diamond point and cause the same to describe a path by moving progressively in straight lines at a desired angle, or in arcs of desired radius, either concave or convex, to generate upon the 45 working surface of an abrasive wheel a profile comprising any desired combination of radial and tangential components, the inter-dimensional relationship of which are very precise.

Our invention has as an object to provide 50 instrumentalities applicable to impart to the working surface of abrasive wheels profiles comprising an infinite variety of radii and straight lines.

Our invention has as another object to provide 55 instrumentalities applicable to hold a diamond

point and cause the same to move in straight lines at any practical angle.

Our invention has as another object to provide 5 instrumentalities applicable to hold a diamond point and cause the same to move in arcs of any practical radius.

Our invention has as a further object to provide 10 instrumentalities applicable to hold a diamond chip and cause the same to trace out concave or convex arcs of predetermined radius.

Our invention has as another object to provide 15 instrumentalities for the stated purpose so proportioned and arranged as to provide a maximum of visibility while in use.

Our invention has as another object to provide 20 instrumentalities for the stated purpose which will give readings in appropriate units of all movements imparted to the diamond.

Our invention has as still another object to 25 provide apparatus which will be light and portable, simple, inexpensive, and convenient to adjust and use.

Further objects, features and advantages of the invention will become apparent upon consideration of the following description together 30 with the accompanying drawings which set forth illustratively an embodiment of the invention.

In the drawings:

Fig. 1 illustrates in elevation fragmentary portions of three abrasive wheels having profiled 35 working surfaces of the type generated by apparatus constructed in accordance with our invention;

Fig. 2 is a front elevation of the illustrative 40 embodiment of our invention mounted in operative position in a surface grinder, only fragmentary portions of which are shown;

Fig. 3 is a side elevation in section taken on the line 3—3 of Fig. 6;

Fig. 4 is a fragmentary section taken on the line 4—4 of Fig. 6;

Fig. 5 is a fragmentary front elevation of Fig. 4;

Fig. 6 is a front elevation of the apparatus according to the invention;

Fig. 7 is a fragmentary section in elevation taken on the line 7—7 of Fig. 6;

Fig. 8 is a bottom view in part section taken on the line 8—8 of Fig. 6;

Fig. 9 is an illustration of an end portion of 50 screw 56, together with a fragmentary portion of endplate 62;

Fig. 10 is a fragmentary right end view of Fig. 8 showing a portion broken away on the line 55 10—10 of Fig. 8; and

Fig. 11 is a top or plan view of the apparatus according to the invention.

In the drawings, in which like characters represent like parts throughout the several views, 5 **20** (Fig. 2) represents an abrasive wheel secured to rotatable spindle **21** of a surface grinder, the frame of which is not shown. **22** represents a conventional guard or housing ordinarily arranged to cover the upper segment of wheel **20**, 10 but adapted to leave the lower part thereof exposed to permit the working surface **23** to contact the work. **24** represents the platen or table of the surface grinder, to which is ordinarily secured a magnetic chuck generally designated **25** 15 having an upper plane fiducial surface **26** and a rear guide rail **27** provided with a front fiducial edge **28** adapted to serve as means for aligning the work accurately in the plane of travel of table **24**. 20 **29** represents the pedestal or frame member of the illustrated embodiment of our invention having accurately finished bottom fiducial surface **30** and rear fiducial surface **31**. Frame **29** is of course constructed of magnetic material 25 such as cast iron so as to be readily held by magnetic chuck **25**.

Appropriately mounted in the device may be a diamond point **32** (Fig. 2) adapted to cut abrasive wheel **20** by contacting the same. Ball 30 cranks **33** and **34** are provided for manual operation to cause diamond **32** to describe a path coincident with the profile desired to be imparted to working surface **23** of wheel **20**. Crank **33** when manually rotated causes diamond **32** 35 to describe an arc, either concave or convex as desired, and of predetermined radius. Crank **34**, when manually rotated, causes diamond point **32** to describe a rectilinear path at a predetermined angle to chuck surface **26** and tangent, if desired, to arcs described by the diamond **32** responsive to rotation of crank **33**.

When properly mounted in the surface grinder, as illustrated in Fig. 2, the device is so positioned that the produced vertical axis of diamond point 45 **32** cuts the rotational axis of spindle **21** of the surface grinder; that is, diamond point **32** is positioned precisely below the center of wheel **20**. The device is purposely designed so that all movements imparted to diamond point **32** occur in a 50 vertical plane parallel to and coincident with the rotational axis of spindle **21**.

Upper portions **29'** and **29''** of frame **29** may be cut away as shown to clear guard **22** of the surface grinder to obviate the necessity of re- 55 moving the same when using the device, and further to provide adequate visibility of the profile being generated. It will be noted that the operator has full visibility when operating the device due to the configuration of the upper 60 portion of frame **29**. This is an important feature of the invention.

Referring now particularly to Figs. 3, 6 and 11, frame **29** may comprise a substantially L shaped member having a lower horizontal foot portion **35** and an integral vertical portion **36**, reinforced by a rear rib **37** and a front rib **38**, and stabilized by a forwardly over hanging foot **39**. Frame **29** may be precisely finished to provide fiducial surfaces **40** and **41** at right angles. 70 Produced in the face **41** of the frame **29** may be a fragmentary annular or arcuate T slot **42**, of constant radius about an origin or center **O—O**, and having a reduced neck portion **43** adapted to slidably receive a mating fragmentary annular lug or tongue **44** integral with a saddle **45** adjust-

ably secured against face **41** by clamping means to be more fully described hereinafter. Saddle **45** may comprise an elongated metallic block having an integral downwardly and outwardly overhanging gib portion **46**, (Fig. 3) coextensive with its longer dimension, and a separate adjustable upwardly overhanging complementary gib member **47**. Gib portion **46** and gib member **47** are complementary and provide a precise, adjustable dovetail channel slidably receiving a mating dovetail slide portion **48** integral with a carriage generally designated **49**.

Rectilinear motion may be imparted to carriage **49** by manual rotation of ball crank **34** which will, when knurled thumb nut **50** is tightened, drive dial **51** together with shaft **52** which is provided with an integral beveled pinion **53** meshing with beveled gear **55** (Fig. 8) having internal threads receiving threaded stationary lead screw **56**. Shaft **52** may have a reduced portion **52'** providing a shoulder **52''** against which the adjacent face of dial **51** may be caused forcibly to abut when thumb nut **50** is tightened. When thumb nut **50** is loosened, dial **51** and/or ball crank **34** may be rotated independently of shaft **52** in order to conveniently make initial or zero settings of dial **51**. Dial **51** may be provided with graduations to indicate in appropriate units rectilinear travel of carriage **49**.

Carriage **49**, (Fig. 8) may have a longitudinal bore coinciding axially with the axis of lead screw **56** in which bushings **57** and **58** may be disposed so that their complementary ends provide precise thrust bearings for beveled gear **55**. Bushings **57** and **58** may be secured to carriage **49** by set screws **57'** and **58'**. Lead screw **56** may have reduced end portions **59** and **60** tightly received by axially aligned apertures in end plates **61**, **62**, which are secured to opposite ends of saddle **45** by screws **63**, **63**, **64**, **64**. Undesired rotation of lead screw **56** may be prevented by the expedient illustrated in Fig. 9 wherein end **60** of screw **56** is machined to provide parallel flats **65**, **65** adapted to be received by a mating slot machined in the inner face of plate **62**.

In order to prevent abrasive grit and other foreign matter from becoming deposited upon the precise way surfaces, lead screw, and gearing, saddle **45** may be provided with slidably overlapping leaf covers **67**, **68**, **69**, and **70**. Covers **67** and **69** may be secured to the opposite ends of carriage **49** by screws **71**, **72**. All of the covers may be provided with sloping way surfaces along their side edges adapted to be closely but slidably received by auxiliary mating way surfaces provided in gib portion **46** and gib member **47** as illustrated most clearly in Fig. 7. Upper covers **67** and **69**, being attached to carriage **49** by screws **71**, **72**, are constrained to move therewith, while covers **68** and **70** are capable of moving outwardly substantially their whole length, but are frictionally restrained from so doing by spring actuated plungers **71'**, **72'** slidably received in appropriate holes in plates **61**, **62**. **65** Covers **68** and **70** may be provided with limit stops comprising inwardly overhanging lips or lugs **68'** and **70'** integral with their outer terminals adapted to abut the outer faces of end plates **61**, **62** at a predetermined point of travel. Motion in the outward direction will be imparted positively to covers **68**, **70** due to abutment of their inner ends with the adjacent faces of carriage **49**, but return motion is imparted by detent drivers consisting of flat cantilever leaf **75**

springs 73, 74 secured at their inner ends to covers 67, 69 by rivets 75, 76.

In order to gain a thorough understanding of the manner in which covers 67, 68, 69 and 70 at all times seal saddle 45, assume, referring to Fig. 8, that carriage 49 is being moved toward the right from the medial position illustrated. Covers 67, 68 and 69 will move with the carriage, but cover 70 will remain stationary due to abutment of stop lug 70' with outer face of end plate 61. If now carriage 49 is returned to the medial position, covers 67 and 69 will return likewise, since they are secured to the carriage, as will also cover 68 due to the driving effect of detent driver 73. Cover 70, however, will remain stationary, being restrained from movement toward the left by frictional restraint of spring-urged plunger 72'. A similar operation would of course ensue if carriage 49 were moved toward the left from the medial position illustrated, with the exception, however, that the operation of covers 68 and 70 just described would be reversed. Hence the covers at all times automatically seal the interior of saddle 45 preventing entrance of abrasive grit, irrespective of the movements of carriage 49.

As previously described, saddle 45 may have an integral fragmentary annular tongue portion 44, Fig. 3, slidably received by neck portion 43 of arcuate T slot 42. Referring now particularly to Fig. 6, face 41 of frame 29 is also provided with a fragmentary circle or sector 71 graduated in degrees of arc throughout a preferable range of 150 degrees, the zero line being at the apex of the lower limb, and the graduations increasing from zero in both clockwise and counterclockwise directions to 90 degrees, providing right and left graduated quadrants. Above the 90 degree points, new upper quadrants are begun which, however, extend only thru a range of 30 degrees, as illustrated.

Saddle 45 may be susceptible of adjustment upon face 41 of frame 29 but is constrained, when moved, to describe a precise arcuate path, about O—O as a center, due to engagement of tongue portion 44 in annular T slot 42. An appropriate fiducial line is provided on saddle 45 for comparison with graduated circle 71. This fiducial line may be engraved at the lower center portion of saddle 45 where material is removed as shown in Fig. 3 to provide a sloping surface 78 in which the fiducial line may be engraved at a point intimate to the graduations of circle 71, in order to avoid parallax errors in making observations.

Saddle 45 may be clamped at the desired angle upon frame 29 by manual operation of a pair of identical clamping devices having handles 79, 79. One of these clamping devices, shown in Fig. 7, will now be described. Saddle 45 may be provided with a vertical threaded hole receiving a mating screw 80, having a lower enlarged cylindrical head 81 in which handle 79 is tightly fitted. The opposite or upper end of screw 80 may constitute a tapering portion 82 terminating in a reduced seat portion 83 rotatively received by a reduced upper portion 84 of the vertical hole in saddle 45. Saddle 45 may also be provided with a horizontal hole 85 whose axis crosses the axis of bore 84 at right angles, and which slidably receives an enlarged head portion 86 of a bolt generally designated 87 having a smaller opposite tail portion 88 joined to head portion 86 by a reduced intermediate neck portion 89. Tail portion 88 is slidably received by arcuate T slot

42 of the frame. The juncture of tail portion 88 and intermediate neck portion 89 provides a shoulder 90 adapted to abut the adjacent shoulder of T slot 42. Head portion 86 of bolt 87 is provided with a transverse tapered hole 92 having an upper enlarged relief or counterbore 93. Tapered portion 82 of bolt 80 is loosely received by bore or hole 92, being normally eccentrically arranged therein. Rotation of screw 80 in the appropriate direction causes axial advance upwardly thereof, forcing tapered portion 82 into contact with the left side of hole 92 rendering a wedging action resulting in axial movement of bolt 87 toward the left whereby shoulder 90 of the bolt is brought forcibly into abutment 15 with the adjacent shoulder of T slot 42.

Hence by appropriate manipulation of handles 79, 79 saddle 45 may be readily clamped or unclamped to face 41 of frame 29. For example, handles 79, 79 may be manipulated in the appropriate manner to unclamp saddle 45, which may then be adjusted to a new position upon frame 29, being guided during adjustment, however, by arcuate T slot 42 which causes the saddle when being adjusted to describe a perfect arc, the magnitude of which may be readily determined by reference to graduated circle 71. In Fig. 6 the axis of movement of carriage 49 would be parallel, of course, to the lower fiducial surface 40 of the frame. However, in Fig. 2, the saddle 30 is shown adjusted to a 45 degree angle with respect to fiducial surface 40, and therefore movement of the carriage would be at a 45 degree angle with respect to the horizontal, which would cause diamond 32 to move in the proper direction to generate surface 23 upon abrasive wheel 35 responsive to rotation of crank 34.

An apron 94, Fig. 3, may be secured to the front face of carriage 49 by two screws 95, 95, and precise mutual alignment of the apron and the carriage may be permanently provided for by a tongue 96 integral with carriage 49 tightly received by a mating groove in the apron. Apron 94 may be provided upon its rear face with an integral fragmentary annular, or arcuate, tongue 97 slidably received by a reduced neck portion 98' of a fragmentary annular or arcuate T slot 98 in a fragmentary annular, arcuate, or substantially crescent shaped way member generally designated 99 having precise arcuate way surfaces 100 and 101. Arcuate T slot 98 and arcuate way surfaces 100 and 101 are circle segments of constant radius about origin or center O—O. Upon way member 99 may be slidably mounted an overhanging carrier arm 102 which may be retained in precise slidable relation by a front plate 103 secured thereto by screws 104, 104 (Figs. 3, 5) and dowel 105. Nested in an appropriate counterbore in the front face of plate 103 may be a cover plate 106 which may be secured to plate 103 by three screws 107, 107, 107. Dowel 105 may serve to align carrier arm 102, front plate 103 and cover plate 106, which three members therefore constitute a unitary assembly precisely slidable upon arcuate way surfaces 100 and 101 and front surface 101' of crescent shaped way member 99. Hence when arm 102 is moved with respect to way member 99, it will be constrained to describe a perfect circular path about origin O—O as a center.

In order to feed carrier 102 with respect to way member 99, a ball crank 33 may be provided (Fig. 4) rotatably mounted upon a reduced stem portion 108 of a shaft 109. An appropriately graduated dial 110 having an elongated, knurled

hub 111 may be also rotatably mounted on stem 108, and in addition a knurled thumb nut 112 may be threaded upon stem 108 at its outer end. In order to provide means for zero adjustment 5 of dial 110, the juncture of reduced stem portion 108 with shaft 109 may provide a shoulder 108' adapted to frictionally engage the adjacent face of dial 110 when axial force is transmitted thru ball crank 33 by tightening thumb nut 112. 10 Hence, thumb nut 112 constitutes a clutch control for permitting rotation of ball crank 33 and/or dial 110 independently of shaft 109. Shaft 109 may be journaled in aligned bearing apertures in plates 103 and 106. Integral with 15 shaft 109 may be a pinion 113 meshing with a gear 114 which drives a pinion 115 thru a shaft 116 journaled in plate 103. Pinion 113 and gear 114 are rotatably nested in an appropriate aperture in plate 103 from which dust is excluded by 20 the cover plate 106 which has been previously mentioned.

Pinion 115 meshes with a fragmentary internal gear segment 117 which may be secured to way member 99 by screws 118. Internal gear segment 117 may be of substantially Z shape in section and may be provided on its outer leg with an integral annular lip or flange 119. Gear segment 117 and way member 99 constitute a unitary assembly which is, when moved with respect to apron 94, constrained to move in an arcuate path of precise circular configuration about origin O—O as a center due to sliding engagement of arcuate tongue 97 in mating neck portion 98' of arcuate T slot 98 together with 35 retaining arcuate flange 119 of gear segment 117.

In order to provide means for indicating the angular relation of way member 99 with respect to apron 94 a graduated circle 120 may be engraved upon the front face 121 of internal gear segment 117 which may be compared with fiducial line 122 (Fig. 6) engraved on the front face of apron 94, and also fiducial line 123' engraved on cover plate 106. For permitting optional adjustment of way member 99 with respect 40 to apron 94, a pair of identical clamping devices 45 may be provided having knurled thumb nuts 123, 123' threaded upon clamp screws 124, 124', one of which is shown in detail in the broken away portion of Fig. 10. Nut 123 is threaded 50 upon screw 124 which has at its opposite end an integral head 125 slidably but not rotatably received by arcuate T slot 98 which has been previously described.

Referring now to Fig. 3, carrier arm 102 may 55 be provided at its free end with an adjustable mount for diamond point 32, which will now be described. Free terminal portion 126 of arm 102 may have a downwardly hanging, elongated, hollow, cylindrical, integral boss 127 having an 60 internal thread in which is precisely and rotatably fitted a threaded sleeve 128 having at its lower end an integral annular flange 129. An externally graduated and knurled micrometer collar 130 may be rotatably journaled upon boss 65 127, and may have at its lower end an inwardly overhanging integral annular flange 131, the inner surface 131' of which is tightly fitted on the adjacent surface of sleeve 128. The outer surface 129' of flange 129 may be a drive fit in the 70 internal mating surface of collar 130 so that collar 130 and sleeve 128 constitute a unitary assembly.

Rotatably received by sleeve 128 may be a lower reduced portion 132 of a quill 133 having 75 a tapered mouth at its upper end adapted to

receive the mating head portion 134 of a cylindrical collet or spring chuck 135 adapted to receive and grip shank 136 in the upper terminal of which diamond point 32 is securely set. To prevent rotation of quill 133, but to permit axial 5 displacement thereof, the latter may be provided with a keyway 137 adapted to slidably receive a cylindrical teat portion 138 of a screw 139 received by an appropriately threaded aperture in an overhanging boss 140 integral with the 10 free terminal of arm 102. A check nut 141 may be provided to prevent undesired rotation of screw 139. Collet 135 may have at its lower end an axially disposed threaded aperture adapted to rotatably receive a mating threaded screw or 15 "draw bar" 142 which passes rotatably thru reduced lower portion 132 of quill 133 and is provided at its lower end with an enlarged, knurled integral head 143. When knurled head 143 is rotated in the proper direction to draw collet 20 135 downwardly, tapered head 134 of the latter is contracted inwardly by the mating tapered mouth of quill 133. Contraction of the diameter of collet 135 is facilitated by three slits 144, 144, 144 which permit resilient contraction or expansion 25 of the diameter of the upper portion of the collet responsive to the influence of tapered head 134 acting in conjunction with tapered mouth of quill 133. Hence collet 135 may be caused optionally to grip or release diamond shank 136 30 upon application of rotational effort in the appropriate direction to knurled head 143 of draw bar 142.

When collet 135 is drawn down to the gripping position, sleeve 128 is capable of free rotation, but is prevented from undesired axial play with respect to quill 133, due to its being closely but rotatably confined axially between the upper face of head 143 and shoulder 133' of the quill 133. Rotation of micrometer collar 130 40 together with associated threaded sleeve 128 causes axial displacement of the same together with collet 135, quill 133, diamond shank 136 and drawbar 142, which axial displacement is precisely responsive to small rotational adjustments 45 of micrometer collar 130. Micrometer collar 130 is of course graduated to read in appropriate units indicating linear axial travel. Hence micrometer collar 130 together with the associated elements just described constitutes feeding 50 means for imparting movement to diamond point 32, the magnitude of which is appropriately indicated by the graduations on the collar.

Now arcuate T slot 42, arcuate T slot 98, and crescent shaped way member 99 are aligned to 55 have a common origin or center O—O; that is to say, they are precise circle segments each having a different radius, but all being struck from the common center or origin O—O. It is desirable to use this origin or center O—O as a 60 datum line for the settings of diamond point 32; and therefore, for this purpose, a gauge 145 (Figs. 3, 11) is provided, comprising a precisely finished rectangular steel block 146 secured by screws 146', 146' to cross bar 147 of a U shaped 65 yoke having spaced parallel arms 148, 148, provided at their free ends with transverse aligned apertures rotatably journaled upon a pair of axially aligned studs 149, 149 securely fitted into aligned side bosses 150, 150 of carrier arm 102. 70 Inner surface or face 151 of gauge block 146 may be of precise arcuate configuration having the central common axis of studs 149, 149 as an origin or center, so that when yoke 147 is swung up vertically, as indicated by the dot-dash line 75

in Fig. 3, about studs 148, 149 as an axis, face 151 of the gauge will coincide precisely with origin or center line O—O. Hence, in preparing the device for generating an arcuate profile, gauge 145 may be swung up to the vertical position, and diamond point 32 brought into contact with the same, after releasing collet 135; and then micrometer collar 130 may be set at zero, after which collet 135 may be again tightened. Diamond 32 may now be either raised or lowered as desired a definite distance either above or below the datum or origin line O—O by appropriate rotation of micrometer collar 130. If diamond point 32 is raised a given distance above the datum line, a concave arcuate path having a radius equal to the distance raised will be described by the diamond 32 when carrier arm 102 is fed along arcuate way member 101 by manual rotation of ball crank 33, or when arcuate way member 99 is adjusted with respect to apron 94, or when saddle 45 is shifted upon the face of pedestal 29. If diamond point 32 is lowered a given distance it will describe a convex arcuate path having a radius equal to the distance lowered, if motion is imparted to the former by any of the adjustments just enumerated. Hence arcs, either concave or convex, and of the desired radius may be generated by first setting diamond 32 at the origin or datum line O—O using gauge 146, and subsequently raising or lowering the diamond by adjusting micrometer 130 to the radius desired.

In operation, the illustrated device according to the invention is first positioned upon the magnetic chuck 25 of the surface grinder, being properly aligned so that rear fiducial edge 31 of the frame 29 is against the adjacent face of rail 27, and so that diamond point 32 is exactly below the center of abrasive wheel 20. Diamond point 32 is now set at origin or datum line O—O in the manner above described, micrometer collar 130 being set at zero. Assuming saddle 45 to be in the normal horizontal position illustrated in Fig. 6, profile *a*, Fig. 1, may be generated by first producing surface *a'*, which may be accomplished by first loosening clamp handles 79, 79 and then swiveling saddle 45 around in a clockwise direction into the southwest quadrant to the angle of face *a'*, after which the saddle is locked in position by tightening clamping handles 79, 79. In swiveling saddle 45 around to the new angular position carriage 49 together with all mechanism associated therewith will swivel with the former, including crescent shaped way member 99. It is desirable to return way member 99 to the original central or normal position shown in Fig. 6, independent of saddle 45, so as to provide a maximum of visibility of the profile being generated and also to provide a maximum of clearance for wheel 20, between surfaces 29' and 29''. In order to bring this about, knurled thumb nuts 123, 123 may be loosened, unclamping way member 99 from apron 94, after which the former may be returned by hand to the position shown in Figs. 2 and 6, after which it may be clamped in this position by again tightening thumb nuts 123, 123. Since it is desirable to dispose the axis of diamond shank 136 in a position normal to the face *a'* while dressing the same, ball crank 33 may be rotated in the appropriate direction to bring this about. Face *a'* may now be generated by feeding the diamond back and forth across the same by rotating crank 34, the depth of successive cuts of the abrasive wheel being regulated by lowering the same progressively by using the vertical feed control commonly furnished as a part of the surface grinder. Surface *a''* may now be generated by adjusting saddle 45 around to the vertical position at 90 degrees, and then neutralizing the corresponding movement of way member 99 by returning the same to the original position as above described, and then feeding diamond 32 up and down vertically by appropriate rotation of crank 34. The convex arc *a'''*, which is tangent to both faces *a''* and *a''''*, may now be generated. This is carried out by first moving diamond 32 downward by appropriate rotation of micrometer collar 130 following which the diamond 32 may be swept thru the correct arcuate path by appropriate rotation of ball crank 33. In adjusting micrometer collar 130 to produce arc *a'''*, diamond 32 is of course lowered a distance equal to the radius of arc *a'''*. The limits of arc *a'''* are of course the points where the same becomes tangent to or meets faces *a''* and *a''''*, and the range of sweep of the diamond necessary to generate arc *a'''* may be correctly maintained by reading dial 110 which indicates in degrees of arc the angular sweep of the diamond. After completing the production of arc *a'''*, face *a''''* may be produced. Face *a''''* is of course tangent to arc *a'''*, and therefore, in passing to the production of face *a''''* the previous adjustment of micrometer collar 130 is not disturbed. However, clamp handles 79, 79 are loosened and saddle 45 swiveled around in counterclockwise direction into the southeast quadrant to the angle corresponding to face *a''''*, and there clamped by tightening clamp handles 79, 79. As above pointed out, the swiveling motion just imparted to saddle 45 will be likewise imparted to way member 99, and since it is desirable to return the latter to the normal central position, this may now be done after loosening thumb nuts 123, 123. After readjusting way member 99 back to normal position, thumb nuts 123, 123 should of course be again tightened. Since saddle 45 is now tilted at the correct angle, face *a''''* may be produced by feeding the diamond back and forth across the same by appropriate rotation of crank 34. Since the adjustment of micrometer collar 130 has not been disturbed, face *a''''* will be precisely tangent to arc *a'''* previously generated.

An infinite variety of profiles, of which *a*, *b*, and *c*, Fig. 1, are illustrative may be readily generated by the device according to our invention. In producing the faces *b'*, *b''* and *b'''* of profile *b* in Fig. 1 the diamond 32 is of course caused to move through the correct angular paths by first setting saddle 45 at corresponding angles on pedestal 29, and then feeding the diamond back and forth by appropriate rotation of crank 34. The arc *b''* is concave, as distinguished from the arc *a'''* of profile *a* which is convex, and to produce this concave arc diamond 32 is of course raised above datum or origin line O—O by adjustment of micrometer collar 130 a distance equal to the radius of arc *b''* after which the same may be generated by appropriate rotation of crank 33.

The principles of operation applicable to the production of profiles *a* and *b* just described above are of course equally applicable to the production of profile *c*, but if desired, faces *c'* and *c''* may be generated by using the transverse table feed control of the surface grinder, which will pass diamond 32 back and forth transversely of the abrasive wheel 20, in a manner similar to that which would be attained by adjusting saddle 45 to the horizontal position and feeding diamond 32

32 back and forth by rotation of crank 34. In preparing the device for the production of arc c'', the diamond would of course be raised above the datum line O—O by adjusting micrometer 5 collar 130 until the same indicates that the diamond has been raised a distance equal to the radius of arc c''. Arc c'' may be generated by passing diamond 32 thru the arcuate path corresponding to the adjustment of micrometer collar 130 as above described. In the production of arc c'' considerable abrasive material of the wheel 20 must be removed, and this may be readily accomplished by beginning the removal of material at the original wheel face coincident with faces c' and c''', and subsequently making successive transits of the diamond 32 around the arc c'' by rotation of crank 34, the wheel 20 being successively lowered for each new cut by appropriate adjustments of the vertical feed device 10 forming a part of the ordinary surface grinder.

It is intended that in generating profiles with the device as above described that the conventional feeding devices forming a part of the surface grinder be utilized so as to remove the correct amount of material from the face of the abrasive wheel at each pass of the diamond. Accordingly, the vertical and horizontal feeds of the surface grinder are preferably used in conjunction with the several control handles of our 15 device in the manner ordinarily employed in the art.

Having thus fully described the invention by disclosing an illustrative embodiment thereof, it is apparent that the same contemplates a device 20 which may be utilized as a portable attachment for surface grinders to generate upon the abrasive wheels thereof an infinite variety of complex profiles consisting of various combinations of radial and rectilinear components the inter-dimensional relationship of which are very precise. The device embodying the invention herein set forth is capable of ready manipulation and it is therefore particularly applicable for the expeditious production of profiles upon abrasive wheels.

45 While we have shown and described in detail a preferred embodiment of our invention, we do not desire to be limited to the precise details herein set forth illustratively, as many modifications may be made within the scope of the invention, 50 which is defined in the following claims.

We claim:

1. In a device of the class described, a mounting element having spaced arcuate arms, a saddle adjustable upon said mounting element in an 55 arc along said arcuate arms, clamping devices for securing said saddle to said mounting element, a carriage slideable on said saddle, manually operable feed mechanism for sliding said carriage, a substantially crescent shaped way member adjustable upon said carriage, a carrier slideable along said way member, manually operable feed mechanism for sliding said carrier, a micrometer head mounted upon said carrier and including a clamping device, a diamond held by said clamping device, and a gauge associated with said carrier for setting said diamond.

2. In a device of the class described, mounting means, an element upon said mounting means adjustable in an arcuate path in a vertical plane 70 thereupon, clamping devices optionally operable for permitting adjustment of said element with respect to said mounting means, a carriage upon said element adjustable in a rectilinear path in a vertical plane thereupon, means for feeding said 75 carriage with respect to said element, an arcuate

way member adjustable in an arcuate path in a vertical plane associated with said carriage, optionally operable clamping devices for permitting adjustment of said way member with respect to 5 said carriage, a carrier slideable with respect to said way member and mounted thereupon, means for feeding said carrier along said arcuate way member, an instrumentality for dressing abrasive wheels adjustably associated with said carrier, and gauge means associated with said carrier and optionally operable for setting said instrumentality.

3. In a device of the class described, a mount having a horizontal foot portion and an integral vertical portion, said vertical portion having an 15 arcuate slot, a saddle adjustable upon said vertical portion and having a tongue engaging said arcuate slot, endplates for said saddle, a stationary screw mounted between said endplates, a carriage having an aperture mounted upon said saddle and 20 slideable therealong, said screw passing thru said aperture, feeding mechanism associated with said carriage and engaging said screw, overlapping dust covers associated with said carriage, a mounting member secured to said carriage and 25 having an arcuate tongue, an arcuate way member adjustable upon said mounting member and having an arcuate groove, said arcuate tongue engaging said arcuate groove in said way member, a carrier slideable upon said arcuate way member, 30 feeding mechanism associated with said carrier for feeding said carrier along said way member, an adjustable micrometer head also associated with said carrier and including clamping mechanism, a diamond clamped by said clamping mechanism, and a gauge swingably associated with said carrier and susceptible of optional operation for setting said diamond.

4. In combination, a frame member having a base portion and a vertically disposed mount portion comprising spaced arcuate arms, a saddle adjustable upon said mount portion, a carriage slideable on said saddle, a crescent shaped way member adjustable on said carriage, a carrier having an overhanging arm slideable along said 40 way member, said overhanging arm extending between said spaced arcuate arms and including a micrometer head positioned above said foot portion, a diamond mounted in said micrometer head, and a gauge associated with said overhanging 45 arm for setting said diamond.

5. In combination, a frame member having a base portion and a vertically disposed mount portion comprising spaced arcuate arms, a saddle mounted on said mount portion and susceptible 55 of adjustment in an arc along said arcuate arms, locking devices for said saddle, a carriage slideable along said saddle, a crescent shaped way member adjustable on said carriage, a carrier slideable along said way member, a diamond adjustably mounted on said carrier, and a gauge associated with said carrier for setting said diamond.

6. In combination, a frame member comprising a foot portion and an integral vertically disposed mount portion having spaced arcuate arms, 65 a saddle mounted on said mount portion and susceptible of adjustment in an arcuate path along said arcuate arms, locking devices for anchoring said saddle to said mount portion at a predetermined point of said arcuate path, a carriage slideable along said saddle, manually operable feed mechanism for sliding said carriage along said saddle, a crescent shaped way member adjustable on said carriage, a carrier slideable along said way member, a diamond adjustably 70

mounted on said carrier, and a gauge associated with said carrier for setting said diamond.

7. In combination, a frame member comprising a foot portion and an integral vertically disposed mount portion having spaced arcuate arms, a saddle mounted on said mount portion and susceptible of adjustment in an arcuate path along said arcuate arms, locking devices for anchoring said saddle to said mount portion at a predetermined point in said arcuate path, a carriage slideable along said saddle, manually operable feed mechanism for sliding said carriage along said saddle, an apron secured to said saddle, a crescent shaped way member mounted on said apron and susceptible of adjustment in an arcuate path, locking devices for anchoring said way member to said apron at a predetermined point in said arcuate path, a carrier slideable along said way member, a diamond mounted on said carrier, and a gauge associated with said carrier for setting said diamond.

8. In combination, a frame member comprising a foot portion and an integral vertically disposed mount portion having spaced arcuate arms, a saddle mounted on said mount portion and susceptible of adjustment in an arcuate path along said arcuate arms, locking devices for anchoring said saddle to said mount portion at a predetermined point in said arcuate path, a carriage slideable along said saddle, manually operable feed mechanism for sliding said carriage along said saddle, an apron secured to said saddle, a crescent shaped way member mounted on said apron and susceptible of adjustment in an arcuate path, locking devices for anchoring said way member to said apron at a predetermined point in said arcuate path, a carrier slideable along said way member, manually operable feeding mechanism for sliding said carrier along said way member, a diamond associated with said carrier, and a gauge also associated with said carrier for setting said diamond.

9. In combination, a frame member comprising a foot portion and an integral vertically disposed mount portion having spaced arcuate arms, a saddle mounted on said mount portion and susceptible of adjustment in an arcuate path along said arcuate arms, locking devices for anchoring said saddle to said mount portion at a predetermined point in said arcuate path, a carriage slideable along said saddle, manually operable feed mechanism for sliding said carriage along said saddle, an apron secured to said saddle, a crescent shaped way member mounted on said apron and susceptible of adjustment in an arcuate path, locking devices for anchoring said way member to said apron at a predetermined point in said arcuate path, a carrier slideable along said way member, a diamond mounted on said carrier, and a gauge associated with said carrier for setting said diamond.

10. In combination, a frame member comprising a foot portion and an integral vertically disposed mount portion having spaced arcuate arms, a saddle mounted on said mount portion and susceptible of adjustment in an arcuate path along said arcuate arms, locking devices for anchoring said saddle to said mount portion at a predetermined point in said arcuate path, a carriage slideable along said saddle, manually operable feed mechanism for sliding said carriage along said saddle, an apron mounted on said saddle, a crescent shaped way member mounted on said apron and susceptible of adjustment in an arcuate path, locking devices for anchoring said way member to said apron at a predetermined point in said arcuate path, a carrier having an overhanging terminal portion slideable along said way member, manually operable feeding mechanism for sliding said carrier along said way member, a micrometer head associated with said carrier and disposed on said overhanging terminal portion, a diamond associated with said micrometer head, a gauge comprising a yoke having a bridge portion and integral spaced arms, said arms being disposed in straddling relation to said terminal portion, and pivot means for permitting swinging motion of said gauge with respect to said terminal portion whereby said bridge portion may be brought into abutting relation with said diamond.

11. In a device of the character described, a frame member provided with a mount portion including arcuate supporting elements, a saddle adjustable upon said mount portion, a carriage movably mounted on said saddle, a crescent-shaped way member adjustable on said carriage, a carrier having an arm overlying and slideable along the way member, said arm being disposed between the arcuate supporting elements and including a micrometer head, a diamond mounted in said micrometer head, and a gauge associated with said overlying arm for setting the diamond.
